UNITED STATES PATENT OFFICE.

GEORGE HENRY MUELLER, OF COLUMBUS, OHIO, ASSIGNOR TO THE JEFFREY
MANUFACTURING COMPANY, A CORPORATION OF OHIO.

CAR-DUMPING APPARATUS.

1,108,465.

Specification of Letters Patent Patented Aug. 25, 1914.

Application filed July 19, 1911. Serial No. 639,306.

To all whom it may concern:

Be it known that I, GEORGE HENRY MUELLER, citizen of the United States, residing at Columbus, in the county of Franklin and State of Ohio, have invented certain new and useful Improvements in Car-Dumping Apparatus, of which the following is a specification, reference being had therein to the accompanying drawing.

10 This invention relates to car dumping apparatus of the type in which the car is tilted to an angle such that material within the car will slide out through an opening in the end.

15 More specifically my invention relates to apparatus such as that disclosed in Patent No. 982,426 for mine car dumping apparatus, issued to Charles A. Griffith, January 28, 1911.

20 My invention has for its object to provide a dumping apparatus of this class having improved means for controlling the movement of a car.

25 Other objects will be apparent from the following specification.

In the accompanying drawings, which form a part of this specification, I have shown that form of mechanism which I now deem preferable. However, it will be obvious that certain changes and modifications may be made within the spirit and scope of my invention.

30 Of the drawings, Figure 1 is a side elevation. Fig. 2 is a plan view, Fig. 3 is a cross sectional elevation taken along the line 3—3 of Fig. 1. Fig. 4 is a cross sectional elevation taken along the line 4—4 of Fig. 1.

35 Referring to the drawings, 1 and 2 represent two substantially horizontal track sections positioned at different elevations. These track sections may be mounted upon any suitable frame work, such as that shown in the drawings. Between these two track sections there is located a connecting section comprising two rails 3, 3. These rails are preferably rectangular in cross section and are narrower than the treads of the ordinary track rails. Each of the rails 3, 3, 45 is shaped to have one part 4 in substantial alignment with the upper main track sec-

tion 1, another part 5 in substantial alignment with the lower main track section 2, and an intermediate sharply inclined part 6 between the parts 4 and 5. 55

7 is a transverse shaft rotatably mounted in suitable bearings 8, 8 secured to the rails 3, 3, preferably on the inclined parts 6, 6.

9, 9 are horns rigidly secured to the shaft 7 at points adjacent and outside of the bearings 8, 8. These horns are adapted to swing with the shaft 7 about the axis thereof into and out of the paths of the wheels of a car on the track. The horns 9, 9 are provided with counter-weighted rearward extensions 60 10, 10, and are preferably formed of cast steel. In order to reduce the expense, the counter-weighted ends of the horns may be provided with cast iron blocks 11. For different installations the blocks 11, may be 65 varied in thickness in order to adapt the mechanism for the peculiar conditions.

75 Stops 12, 12 are provided on the inclined parts 6 of the rails, these stops being adapted to engage the horns to limit their upward movement. It will be observed that the two horns are engaged simultaneously and that there is on this account no tendency for torsional strains to be set up in the shaft 7. At one end of the shaft 7 there is provided 80 a brake wheel 13 which is provided with a V-shaped circumferential groove. 14 is a brake band for the wheel 13. To this brake band are secured wearing blocks 15 which are shaped to engage with the groove of the 85 wheel and to be thus held in alignment therewith.

16 is a rock shaft mounted in bearings suitably connected with the rails. The shaft extends parallel with the shaft 7. At 90 one end of the shaft 16 is an operating lever 17 which is provided with a handle 18. Secured to the shaft 16 in respective alignment with the horns 9, 9 are two stop dogs 19. When in the position shown in Fig. 1, 95 the dogs 19 engage the ends of the horns 9, 9, and serve to prevent their movement in the direction of the arrow. It will be observed that the ends of the horns are formed in the arc of a circle which, when the horns 100 are in the position shown, is concentric with the axis of the rock shaft 16. As a result of

this construction the horns are held always in the same position irrespective of the exact position of the dogs.

The hand lever 17 is provided with a downward extension 20 to the lower end of which there is pivotally connected one end of a horizontal link 21. The other end of this link is pivotally connected with the lower end of the lever 22 which is rigidly secured at its upper end upon a suitably mounted rock shaft 23. The rock shaft 23 also carries a lever 24 at the outer end of which are pivotally connected depending links 25.

26 is a lever which is pivoted intermediate its ends upon the shaft 16. One part 26^a of the lever 26 consists of two forks which extend horizontally and which carry a shoe 27 adapted, when in proper position, to engage with the brake wheel 13. The other part 26^b of the lever 26 also extends substantially horizontally but is offset into a plane below that of the part 26^a. The outer end of the part 26^b is pivotally connected with the lower ends of the links 25. Slidably mounted upon the part 26^b is a weight 28 which may be secured in any one of a plurality of positions by means of a pin 29 which is adapted to extend through any one of the apertures 30. While I have described the parts 26^a and 26^b as comprising one single lever, it will be understood that for convenience of construction, these may be made as separate parts and bolted or otherwise secured together. When completed, however, they constitute one rigid whole.

One end of the brake band 14 is secured in any desired manner to the main track supporting frame. The other end has secured to it a threaded rod 31 which extends through an aperture in a yoke 32 which is pivotally mounted between the two forks of the lever part 26^a. The position of the rod 31 with respect to the yoke may be adjusted by means of the lock nuts 33 and 34.

35 indicates a car in dumping position. Any desired type of car adapted for the purpose may be used. The end door may be opened either by hand or by any desired mechanical means. In the drawings, I have indicated substantially horizontal bars 36 for engaging the door parts to hold them relatively elevated when the car is in dumping position. However, other means may be used, if preferred. 37 is a chute mounted beneath the rails 3, 3 for receiving the coal or other material as it slides from the car.

In operation let it be assumed that there is no car on the dump and that the horns 50 are in the position marked "a." Let it also be assumed that the lever 17 and the parts connected with it are in the position shown in the drawings, the brake band 14 being tensioned by means of the weight 28. As a loaded car approaches dumping position, its

forward wheels are engaged by the two horns 9, 9, and the car is gradually brought to rest because of the resistance offered to the movement of the horns by the brake. The dogs 19 engage the rear ends of the 70 horns 9, 9 and temporarily maintain them in the position designated by "b" and shown by full lines in Fig. 1. The car is maintained in this position until its contents have been discharged through the opened end. After the discharge of the contents of the car, the operator moves the lever 17 in the direction of the arrow sufficiently to release the dogs 19 from engagement with the rear ends of the horns. By means of the 80 system of linkage which has been described, the lever 26 is at the same time moved sufficiently to release the brake band 14 and simultaneously apply the brake shoe 27. The lever system interposed between the 85 hand lever 17 and the lever 26, is a force increasing one and a relatively small force applied to the handle 18 is sufficient to move the lever 26 and raise the relatively heavy weight 28. The horns 9, 9, after being released by the dogs 19, are free to move under the weight of the car 35 inasmuch as the 90 brake band 14 has been released simultaneously with the movement of the dogs. A relatively small braking effect is applied 95 to the wheel 13 by means of the shoe 27, but this is not sufficient to materially retard the movement of the horns under the weight of the car from the position "b" to the position "c." However, the braking effect of 100 the shoe 27 is sufficient to prevent the return of the horns by the action of gravity to the position "a." Therefore, the horns may be held by the operator in the position "c" until the rear wheels of the car have passed. Were it not for the shoe 27, or its equivalent, the horns would return under the action of 105 gravity and would engage with the rear wheels of the car and possibly cause derailment. After the rear wheels of the car have 110 passed the horns, the operator releases his hold on the handle 18 and the weight 28 immediately causes the shoe 27 to be moved out of engagement with the wheel 13, the brake band 14 to be tensioned, and the lever 17 to 115 be returned to its normal position. The operator, by retarding the return movement of the lever 17, will give the horns opportunity to return by gravity to position "a" after the release of the shoe 27, and before 120 the application of the braking effect on the band 14.

It will be observed that by my improved construction I have provided means whereby the movement of the car may be completely controlled by the operator with a minimum of effort by means of a single lever. The brake is automatically applied by the weight 28, but the normal braking effect of the weight may be gradually in- 130

creased or diminished by a slight pressure on the handle 18. By varying the braking effect, a car may be brought to rest slowly or rapidly as is desired. Furthermore, the retarding effect of the apparatus may be varied to correspond with the weight of a car and also with its velocity as it approaches the dump.

The normal braking effect applied through the band 14 may be adjusted by changing the position of the weight 28. The position of the brake shoe 27 when the band 14 is tensioned may be regulated by means of the nuts 33—34 on the rod 31.

I do not claim broadly as part of my present invention the combination of pivoted car stopping horns and a brake as this combination is disclosed and claimed in an application by another inventor now pending before the Patent Office.

What I claim is:

1. In a car dumping apparatus, the combination of a track, a car engaging device movable in the same general direction as the car from a point in the path thereof to a point out of the path thereof, a brake connected with the car engaging device and adapted to resist its movement together with that of the car, the said device being freely movable except as retarded by the brake, a stop dog, an element rigidly connected with the car engaging device and adapted to be positively engaged by the dog to arrest the movement of the said device, and means for releasing the stop dog from the said element and at the same time releasing the brake to permit the movement of the car engaging device in its initial direction out of the path of the car.

2. In a car dumping apparatus, the combination of a track, a device mounted for reciprocable movement and arranged when in one extreme position to engage a car on the said track and when in the other extreme position to lie outside of the path of the car, a brake connected with the device and adapted to resist its movement together with that of the car, the said device being freely movable except as retarded by the brake, a stop dog, an element rigidly connected with the reciprocable device and arranged to be positively engaged by the stop dog to arrest the movement of the device together with that of the car, means for moving the stop dog out of engagement with the said element and for releasing the brake whereby the device is permitted to move to its extreme position out of the path of the car, and means for returning the said device to its initial extreme position.

3. In a car dumping apparatus, the combination of a track, an oscillatory device arranged when in one extreme position to engage a car on the said track and when in its other extreme position to lie outside of the

path of the car, a brake connected with the device and adapted to resist its movement together with that of the car, the said device being freely movable except as retarded by the brake, a stop dog, an element rigidly connected with the oscillatory device and adapted to be positively engaged by the stop dog to arrest the movement of the device and of the car, means for moving the stop dog out of engagement with the said element and for releasing the said brake whereby the device is permitted to move to its extreme position out of the path of the car, and means for returning the oscillatory device to its initial extreme position.

4. In a car dumping apparatus, the combination of a track, a pivotally mounted device adapted to engage a car on the track, a brake connected with the pivotally mounted device and adapted to resist its movement together with that of the car, the said device being freely movable except as retarded by the brake, a stop dog, an element rigidly connected with the said device and arranged to be positively engaged by the stop dog to arrest the movement of the device and of the car, and means for moving the stop dog out of engagement with the element and for at the same time releasing the brake whereby the pivotally mounted device is permitted to move in its initial direction out of the path of the car.

5. In a car dumping apparatus, the combination of an inclined track, a reciprocable device arranged to engage a car on the said track when in one extreme position and to lie outside the path of the car when in its other extreme position, a brake connected with the said reciprocable device, the device being freely movable except as retarded by the brake, a stop dog, an element rigidly connected with the device and adapted to be engaged by the stop dog to arrest the movement of the device together with that of the car, means for moving the stop dog out of engagement with the element and for simultaneously releasing the brake whereby the device is permitted to move in its initial direction out of the path of the car, automatic means for returning the reciprocable device to its initial position, and manually controlled means for retarding the return movement.

6. In a car dumping apparatus, the combination of an inclined track, an oscillatory device arranged to engage a car on the inclined track when in one extreme position and to lie outside of the path of the car when in its other extreme position, a brake connected with the device and adapted to resist its movement together with that of the car, the said device being freely movable except as retarded by the brake, a stop dog, an element rigidly connected with the reciprocable device and adapted to be engaged

5 by the stop dog to arrest the movement of the device together with that of the car, means for moving the stop dog out of engagement with the element and for simultaneously releasing the said brake whereby the device is permitted to move to its extreme position out of the path of the car, automatic means for returning the device to its initial extreme position, and manually controlled means for retarding the said 10 return movement.

15 7. In a car dumping apparatus, the combination of an inclined track, a reciprocable device arranged to engage a car on the inclined track when in one extreme position and to lie outside of the path of the car when in its other extreme position, a brake for resisting the movement of the device together with that of the car, the said device 20 being freely movable except as retarded by the brake, a stop dog, an element rigidly connected with the reciprocable device and adapted to be engaged by the stop dog to arrest the movement of the device together 25 with that of the car, a manually movable lever connected with the stop dog and with the brake whereby the former may be moved out of engagement with the element and the latter simultaneously released to permit 30 movement of the reciprocable device to its extreme position out of the path of the car, means for automatically returning the device to its initial extreme position, means for retarding the said return movement, and a 35 connection between the retarding means and the lever whereby the retarding means may be made operative.

40 8. In a car dumping apparatus, the combination of an inclined track, an oscillatory device arranged to engage a car on the track when in one extreme position and to lie outside of the path of the car when in its other extreme position, a brake connected with the oscillatory device and adapted to resist 45 its movement together with that of the car, the said device being freely movable except as retarded by the brake, a stop dog, an element rigidly connected with the oscillatory device and adapted to be engaged by the 50 stop dog to arrest the movement of the oscillatory device together with that of the car, a lever connected with the stop dog and with the brake and adapted when moved to simultaneously release them to permit the movement 55 of the device to its extreme position out of the path of the car, automatic means for returning the device to its initial extreme position, and means for retarding the return movement, the said retarding means 60 being connected with the said lever in a manner to be made operative by the movement thereof.

65 9. In a car dumping apparatus the combination of an inclined track, a reciprocable device arranged to engage a car on the track

when in one extreme position and to lie outside the path of the car when in its other extreme position means for retarding the movement of the reciprocable device together with that of the car, a stop for arresting the movement of the reciprocable device to hold the car in dumping position, means for simultaneously releasing the reciprocable device from the arresting means and from the retarding means whereby the device is 70 permitted to move in its initial direction to a position out of the path of the car, automatic means for returning the reciprocable device to its initial position, and manually controlled means for retarding the return 75 movement.

80 10. In a car dumping apparatus, the combination of an inclined track, an oscillatory device arranged to engage a car on the inclined track, when in one extreme position and to lie outside of the path of the car when in its other extreme position, a retarding mechanism connected with the oscillatory device and adapted to resist its movement together with that of the car, means for 85 arresting the movement of the oscillatory device to hold the car in dumping position, means for simultaneously releasing the retarding mechanism and the arresting means to permit the oscillatory device to move to its extreme position out of the path of the car, automatic means for returning the device to its initial extreme position, and manually controlled means for retarding the said 90 movement.

95 11. In a car dumping apparatus, the combination of an inclined track, a reciprocable device arranged to engage a car on the inclined track when in one extreme position, a retarding mechanism connected with the device and adapted to resist its movement together with that of the car, means for 100 arresting the device to hold the car in dumping position, a manually movable lever for simultaneously releasing the retarding mechanism and the arresting means to permit movement of the reciprocable device to its other extreme position out of the path of the car, means for automatically returning the device to its initial extreme position, means for retarding the return movement, and a connection between the said 105 return retarding means and the lever whereby the said retarding means may be controlled.

110 12. In a car dumping apparatus, the combination of an inclined track, an oscillatory device arranged to engage a car on the track when in one extreme position and to lie outside of the path of the car when in its other extreme position, a retarding mechanism connected with the oscillatory device and adapted to resist its movement together with that of the car, means for arresting the movement of the oscillatory device to hold 115 120 125 130

- the car in dumping position, a lever connected to simultaneously release the retarding mechanism and the arresting means to permit movement of the oscillatory device 5 to its extreme position out of the path of the car, automatic means for returning the oscillatory device to its initial extreme position, and means for retarding the return movement, the said return retarding means being connected with the lever in a manner to be made operative by the movement thereof. 10
13. In a car dumping apparatus, the combination of an inclined track, horns pivotally mounted to extend into the path of the 15 wheels of a car on the said track, means for resisting the movement of the horns together with that of a car, and pivotally mounted stop dogs adapted to engage respectively with the horns to arrest their 20 movement, each of the said horns having a dog engaging surface which is concentric with the pivotal axis of the dogs when the horns are in engaged position.
14. In a car dumping apparatus, the combination of an inclined track, a pair of pivotally mounted horns adapted to engage the 25 wheels of a car on the track, a brake wheel operatively connected with the horns, a brake band engageng the brake wheel, a lever 30 for tensioning the brake band, a weight adjustable to various positions along the lever, and positive means for arresting the movement of the horns to hold the car in dumping position.
- 35 15. In a car dumping apparatus, the combination of an inclined track, a pair of pivotally mounted horns adapted to engage the wheels of a car on the track, a brake wheel connected with the horns, a brake band engageng the wheel, a weighted lever for tensioning the brake band, a hand lever for increasing or diminishing the tension of the 40 brake band, and positive means for arresting the movement of the horns to maintain the car in dumping position.
- 45 16. In a car dumping apparatus, the combination of an inclined track, a pair of pivotally mounted horns arranged to engage the wheels of a car on the track, a brake wheel 50 operatively connected with the horns, a brake band engaging the wheel, a lever for tensioning the brake band, a weight adjustable to different positions along the lever, a hand lever for increasing or diminishing 55 the tension of the brake band, and positive means for arresting the movement of the horns to maintain the car in dumping position.
- 60 17. In a car dumping apparatus, the combination of an inclined track, a pair of pivotally mounted horns adapted to engage the wheels of a car on the track, a brake wheel connected with the horns, a brake band engageng the wheel, a lever for tensioning the 65 brake band, a weight on the lever, a hand lever, a force increasing connection between the hand lever and the brake lever whereby the latter may be moved by the former to lift the weight and release the brake band, and positive means for arresting the movement of the horns to maintain the car in 70 dumping position.
18. In a car dumping apparatus, the combination of an inclined track, a pair of pivotally mounted horns arranged to engage the wheels of a car on the track, the horns being movable in the general direction of movement of the car to a point outside of the path of the car wheels, means for stopping the horns at points intermediate the 75 ends of their paths to maintain the car in dumping position, a brake connected with the horns and adapted to resist their movement and that of the car, means for automatically applying the brake, a hand lever, means connected with the hand lever for releasing the horns to permit their movement to positions outside of the path of the car 80 wheels, and means connected with the hand lever for releasing the brake simultaneously with the release of the horns. 85
19. In a car dumping apparatus, the combination of an inclined track, a pair of pivotally mounted horns arranged to engage a car on the track and to move in the general 90 direction of movement of the car to positions outside of the path of the car wheels, means for arresting the movement of the horn at points intermediate the ends of their paths, a brake connected with the horns, means for automatically applying the brake, automatic means for returning the horns from their positions outside of the path of the car 95 wheels to their normal car when engaging positions, a hand lever, and means connected with the hand lever for simultaneously releasing the horns, releasing the brake and applying a retarding force to prevent the movement of the horns by the said returning means. 100
20. In a car dumping apparatus, the combination of an inclined track, a transverse rotatable shaft beneath the track, two horns on the shaft arranged to extend into the path of the wheels of a car on the track, and 105 to be moved in the general direction of movement of the car to points outside of the path of the wheels, a brake wheel on the said shaft, a brake band engaging the wheel, a second transverse shaft, a hand lever for oscillating the second shaft, two dogs rigidly connected to the second shaft and positioned to engage the horns on the first shaft to 110 temporarily stop them to maintain the car in dumping position, a lever pivoted on the second rock shaft and connected with the brake band, a weight on the lever for moving it to tension the brake band, and connections between the brake lever and the hand lever whereby the latter is moved to release the 115 120 125 130

brake when the former is moved to release the dogs from engagement with the horns.

21. In a car dumping apparatus, the combination of a fixed inclined track, a brake, 5 means for regulating the action of brake, a pair of horns movable longitudinally of the track and adapted to engage a car on the track, the said horns being connected with the brake but otherwise freely movable, a 10 stop for arresting the movement of the said

horns, and means for releasing the stop to permit the horns to move onward in the initial direction.

In testimony whereof I affix my signature, in presence of two witnesses.

GEORGE HENRY MUELLER.
